UNITED STATES PATENT OFFICE.

WALTER PRESTON HENDON, OF DALLAS, TEXAS.

DESIGN FOR A PLOW-BEAM FOR DOUBLE-DISK PLOWS.

SPECIFICATION forming part of Design No. 33,113, dated August 21, 1900.

Application filed May 17, 1900. Serial No. 17,071. Term of patent 14 years.

To all whom it may concern:

Be it known that I, WALTER PRESTON HENDON, a citizen of the United States, and a resident of the city of Dallas, county of Dallas, 5 and State of Texas, have invented and produced a new and original Design for Plow-Beams for Double-Disk Plows, of which the following is a specification, reference being had to the accompanying drawings, forming 10 part thereof.

Figure 1 is a plan view of a plow-beam embodying my design. Fig. 2 is an elevational view of the beam shown in Fig. 1.

As shown in the drawings, the beam is in 15 the form of an open frame having two long substantially-parallel members A and B, having between them at their forward ends a spacing block or piece C. The rear ends A' and B' of the members A and B extend at an 20 angle to the main portions of the members and substantially parallel to each other. At

the rear end of the part B' is a bracket D, of the shape shown, and from the bracket D a frame member E extends forward for part of its length substantially parallel with the member B and at its forward portion is inclined to join said member B. 25

The essential feature of the design is the frame having the parallel members A B, terminating in angular ends, and the member E 30 substantially parallel with the member B for a part of its length and joining the same at the forward portion.

Having described my invention, what I claim as new, and desire to secure by Letters 35 Patent, is—

The design for a plow-beam for double-disk plows as herein shown and described.

WALTER PRESTON HENDON.
